FIGURE 7 is a perspective view of a plastic jug showing another embodiment of my design with a handle and wherein the finish rises directly from the body of the jug rather than from a sloping shoulder;

I claim:

The ornamental design for a plastic jug, as shown and described.
